UNITED STATES PATENT OFFICE.

NAPOLEON J. PERRY, OF NASHVILLE, TENNESSEE, ASSIGNOR TO MAY HOSIERY MILLS,
OF NASHVILLE, TENNESSEE, A CORPORATION OF TENNESSEE.

DIAL-CAM-CONTROLLING MECHANISM.

Application filed September 13, 1920, Serial No. 409,983. Renewed March 23, 1928.

The purpose of my said invention is to provide an improvement in dial cam controlling means designed especially for use in circular knitting machines adapted to knit successive portions of plain work (either by circular or reciprocating motion) and rib work in predetermined relation thereto, as for example a stocking with a plain foot and ribbed leg. While this device is particularly adapted for use in a knitting machine having a stationary needle cylinder and a rotary cam ring, it is not limited thereto, certain features being adapted to machines having a stationary cam ring and rotary needle cylinder, as well as to knitting machines of other types, and to other pattern-controlled machinery.

Reference is had to my co-pending application No. 348,071, filed December 29, 1919, for details of structure not herein disclosed.

Referring to the accompanying drawings which are made a part hereof and on which similar reference characters indicate similar parts,

Figure 1 shows a detail elevation taken at one side of the machine,

Figure 2 a plan view of the machine, parts not necessary to this disclosure being omitted,

Figures 3 and 4 are details,

Figure 5 a view showing the under side of my positioning cams,

Figure 6 a section of the cam in Figure 5, and

Figure 7 a view showing the under side of the dial cam-plate.

The cam shaft 25 is driven by pawls engaging ratchets 26 and 27 fast thereon, and has also fast thereon a motion changing cam

40 28 and a pattern drum 29 for controlling the yarn feeds and other devices. Loose on the shaft is a hub 30 bearing a ratchet 31 by which it is driven from a moving part of the machine, and a sprocket wheel 32, on which

45 is a chain 33. These parts are or may be all as in the patent to Mayo, 726,178, and operate in the same manner or other pattern forms may be substituted for the sprocket chain, if preferred.

50 To adapt this mechanism for controlling also the cams in a dial cam plate, I have added the following parts, as described.

The chain has sidewise extensions 34 on

certain links which are adapted to engage a downward extension 35 on a lever 36 pivoted at 37 to a fixed part of the machine. A vertical rod 38 rests at its lower end on lever 36 and carries at its upper end a plate 39 to which it is rigidly connected. A rod 40 is also fixed to the plate and both rods are guided by a fixed bracket 41.

A segmental rack member 42 is fixed to rod 40 above plate 39 and is adapted to operate pinion 43. This pinion is mounted on a shaft 44 having a crank-pin 45 for moving two pawls 46 and 47. Pawl 47 is pivoted by a screw 48 to an arm 49 on a post 50 on the rotating head 51 of the machine. Pawl 46 drives ratchet 52 and pawl 47 acts to lock it after each movement by pawl 46.

70 The number of teeth in rack segment 42 and pinion 43 is so proportioned that shaft 44 will make a complete revolution each time it is engaged by rack 42. Ratchet 52 has 24 teeth and is formed on a positioning cam 53 mounted upon the dial cam plate or support

54 on the under side of which is a pivoted block carrying a needle-projecting cam 55. The positioning cam is capable of rotation

80 relative to the plate 54 to move the cam 55 to desired positions by the action of cam path 56 on a pin 57, projecting from the block, as knitting position, where the needles are fully projected and fully retracted during a relative rotation of the needles and

85 their cams; tucking position where the needles are projected far enough to take the yarn, but not to clear their latches to knit, and welting position where they remain substantially in non-knitting position and may

90 be bare of yarn or may hold loops of yarn for a desired period. It also moves a pivoted block carrying cam 58 by the action of cam path 59 on pin 60 to a position where it clears the latches of the needles and to an inner

95 idle position to cast off the loops. Needle-retracting cams and guard cams are also carried by the blocks, as in my prior application above mentioned.

100 In a machine such as that of my application No. 348,071, the positioning cam of Figure 5 would produce effects as follows on the dial needles 24 in its scheduled positions of rotary adjustments, the positions of the pins projecting upwardly from the dial cams 105 into grooves 56 and 59 being indicated by

the numbered lines in Figure 5, the operations indicated taking place during the knitting of a stocking from toe to top.

5	Number	Position of cam	Effect on knitting
	24	Welting...	Plain work on cylinder.
	1	Tucking...	Dial needles take yarn.
	2	Welting...	Hold bights of yarn.
	3	Welting...	Hold bights of yarn.
10	4	Knitting...	Change from plain to rib completed.
	5	Tucking...	Needles take yarn from round welt.
	6	Welting...	(Dial needles hold bights—cylinder
	7	Welting...	needles knit to make ordinary round
	8	Knitting...	welt.
	9 to 12	Repeat operations 5 to 8 for second round welt.	
	13 to 16	Repeat operations 5 to 8 for third round welt.	
	17 to 20	Repeat operations 5 to 8 for fourth round welt.	
15	21	Tucking...	Change from rib to plain.
	22 and 23	Welting...	Change from rib to plain.
	24	Welting...	Plain work on cylinder.

It will be understood that the leg of the stocking is knit at position 4, and that the 20 round welts referred to are merely for ornamenting the upper end of the stocking, they being knitted as ordinary welts, and the stockings being knitted as endless string work. Also that in changing from plain to 25 rib, at positions 2 and 3 two or more rounds are knit on the cylinder needles while the dial needles hold bights of yarn taken at position 1.

When position 22 is reached for the knitting cam, the work casting cam is at position 11 just about to advance the needles, which have ceased to take yarn at 22; at position 23 of cam 55, cam 58 is at position 12 to clear the latches, and when cam 55 is 35 at 24, cam 58 is at 13 and the dial needles cast off their stitches, while the cylinder needles continue to knit thus completing the cycle. It is to be understood that the positions indicated by circles in Figure 5, are 40 really those of the upwardly projecting lugs on the cams and not of the cams themselves, this being the reason why 23 and 12, e. g., are not at diametrically opposed points.

Such description of the operation of cam 45 53 is merely illustrative and its operation may be widely varied by using different positioning cams and by changing the pattern mechanism.

An advantage of this device is that by the 50 use of the positioning cam shown having twenty-four positions instead of eighteen as in my former application, I am enabled to dispense with one rack-segment and the entire series of devices necessary to lift the rack-segment to high position. It will be noted that application 348,071 has two 55 series of lugs on the pattern form for raising its segment-racks to different heights, while the present drive employs but one set of lugs on the chain, yet is able to knit plain and ribbed fabric with roll welts in the ribbed fabric.

Another advantage is that the angles of the outer cam path are easier, thus facilitating 60 the running of the machine.

As shown in application No. 409,981, the pattern wheel and one-half of the duplex rack of the earlier construction may be dispensed with, the single rack being operated 70 by lugs of uniform height on the pattern drum.

I have shown one form of my invention but wish it to be distinctly understood that I do not limit myself to the particular embodiment shown or the particular utility described, the true scope of the invention being 75 set forth in the appended claims.

Having thus fully described my said invention, what I claim as new and desire to secure by Letters Patent, is:

1. In a dial and cylinder knitting machine a dial cam support, needle operating cams on the same, pins on the cams, a positioning cam for the needle cams, the positioning cam having grooves therein for engaging said pins on the needle cams and means for indicating twenty-four successive positions of the needle-cams, substantially as set forth.

2. In a knitting machine adapted to produce either ribbed, plain circular or reciprocating work as desired, a dial cam support, needle cams thereon, a rotary positioning cam on the support to adjust the needle cams, a ratchet on the cam having twenty-four teeth, and means for operating the 95 ratchet.

3. In a knitting machine adapted to produce either ribbed, plain circular or reciprocating work as desired, a dial cam support, needle cams thereon, a rotary positioning 100 cam on the support to adjust the needle cams, a ratchet on the positioning cam having twenty-four teeth, and pattern controlled means for operating the ratchet comprising a pinion and a rack rotatable relatively to each other, and means for moving them relatively into and out of engaging 105 position.

4. In a knitting machine adapted to produce either ribbed, plain circular or reciprocating work as desired, a dial cam support, a rotary positioning cam on the support, means to rotate the cam in a cycle of twenty-four steps, a single pinion rotatable with the dial cap, a single rack adapted to engage 115 the pinion, a pattern chain and connections therefrom to move the rack into and out of operative relation to the pinion.

5. In a knitting machine adapted to produce either ribbed, plain circular or reciprocating work as desired, a dial cam support, a rotary positioning cam on the support, and means to rotate the cam in a cycle of twenty-four steps, a single pinion rotatable with the dial cap, a single rack adapted to engage 125 the pinion, a pattern mechanism to control the operations of the machine, including a pattern chain and connections therefrom to move the rack into and out of operative relation to the pinion.

6. In a knitting machine adapted to produce either ribbed, plain circular or reciprocating work as desired, a dial cam support, a main cam shaft, a sprocket wheel loose thereon, a chain on the wheel, lugs projecting laterally from the chain, a pinion on the rotating head of the machine for positioning the dial cams, a rack adjacent thereto, and means actuated from the chain for moving the rack into and out of operative relation to the pinion.

7. In a pattern mechanism the combination of a chain having lugs projecting laterally therefrom, a lever adapted to engage 15 the lugs, an upright rod movable with the lever, a rack on the rod for engagement with a pinion on the knitting head, a bracket for guiding the upper end of the rod and a second rod fixed to the first and also guided 20 by the bracket, the rack being movable by the lugs on the chain into and out of operative relation to the pinion.

8. In a pattern mechanism, a main cam shaft, a pattern form supported thereby 25 said form having a single series of projections at one side, a lever adapted to rest at one end on the projections, a rod connected to the lever, a segment rack on the rod, a positioning cam for the dial cams, said positioning cam carrying a ratchet, a shaft having 30 a star-wheel for engagement with the segment rack and an eccentric pawl for operating the ratchet.

9. In a knitting machine having rotary 35 needle actuating cams, a sprocket, means to drive the same, a chain on the sprocket, lugs projecting perpendicularly to the path of movement of the chain, lugs projecting laterally from the chain, a pivoted lever

arranged to be moved by the lugs, a device 40 movable about the axis of the machine, and an abutment adjusted to be moved by said lever into the path of said device for variously positioning one of said needle-actuating cams, substantially as set forth. 45

10. In a dial and cylinder knitting machine, a positioning cam above the dial connected to the dial cams to adjust them and thereby vary the action of the needles, a pinion on the rotary head of the machine, 50 connections from the pinion for operating the positioning cam, a single rack to operate the pinion, a pattern form having a single series of elevations of uniform height and connections adapted to be lifted by the form 55 to place the rack in operative position, substantially as set forth.

11. In a dial and cylinder knitting machine, a rotary head, a pinion thereon connected to a dial cam for adjusting it, a 60 single rack on a stationary part of the machine for driving the pinion, and pattern mechanism for moving said rack into and out of driving position, substantially as set forth. 65

12. In a dial and cylinder knitting machine, a rotary head, a pinion thereon connected to a dial cam for adjusting it, a rack for driving the pinion, a pattern form having a single series of elevations of uniform 70 height, and connections from the form to the rack, substantially as set forth.

In witness whereof, I have hereunto set my hand at Nashville, Tennessee, this 9th day of September, A. D. nineteen hundred and 75 twenty.

NAPOLEON J. PERRY.
